6 Claims. (Cl. 257—245)

1

This invention relates to external combustion gas engines and more particularly to improvements thereof which enable such engines to operate with an efficiency approaching the theoretical value and to perform with characteristics desirable for driving both stationary and mobile devices.

It is an object of this invention to provide an improved external combustion gas engine wherein a thermo-gas compressing unit serves as a gas compressor for supplying gas under pressure to a storage receiver for use in operating both auxiliary equipment and also one or more gas engines which may be remotely positioned from the receiver and compressor.

In brief, external combustion gas engines which have heretofore been known in the art have been subject to many limitations. Such engines employ a loosely fitting air moving plunger which serves to move air from a cool to a hot portion of a cylinder and vice versa. The periodic heating and cooling of the air causes a change in pressure which serves through a power piston to operate the output shaft of the engine. A source of heat such as burning fuel is employed to heat the gas in one end or portion of the cylinder, and a heat extracting device is employed at the opposite end of the cylinder in order to reduce the temperature of the gas after it had passed from the hot end of the cylinder to the cold end of the cylinder. During the transfer of gas between the cylinder ends, it passes through a heat regenerator or storage means which serves to absorb a portion of the heat from the heated gas and to liberate the stored heat to the gas as it passes from the cooled end of the cylinder to the hot end. The resulting expansion and contraction of the gaseous medium was employed to move a piston to provide the power output from the engine.

The best known engines employing this principle of operation are those disclosed by Sterling, Rider, Ericsson and other early pioneers. These engines found limited use and were subject to the disadvantage resulting from the necessity of being constructed in large size with a resulting heavy weight. The time necessary for the transfer of heat in the above described cycles of known engines is so great that the engine must be operated at slow speeds, that is, with relative few cycles per minute. It is apparent that the smaller the number of cycles in a given period of time, the greater must be the energy made available per cycle and hence the greater the size of the engine which is necessary in order to deliver a given amount of power.

While the mechanical features of the previously known external combustion gas engines have differed, they have all followed the general pattern of employing the expanding and contracting gas within the heated cylinder to move

2

a piston from which power was derived through mechanical linkages. Due to their mechanical limitations, it has been impossible satisfactorily to power mobile devices such as automobiles, ships and the like with these engines. Further, the efficiency has been low in respect to the efficiency which may be theoretically attained. Also, it has been impossible due to mechanical and material limitations to provide an external combustion gas engine having an efficiency and a power output comparable with engines designed to operate on other principles such, for example, as the internal combustion engine.

It is, therefore, another object of the invention to provide an improved external combustion gas engine which may be operated at high efficiency throughout a varying pressure range and over a wide range of speeds and torques.

Another object of this invention is to provide an improved external combustion engine, the output of which is independent of atmospheric pressures and is increased with lowered atmospheric temperatures.

Another object of this invention is to provide an improved engine of the external combustion type which may be operated at high efficiency on any liquid, or gaseous fuel, including oils having volatility and low B. t. u. content.

Another object of the invention is to provide an improved external combustion engine which may be readily reversed in direction, is non-stallable upon the sudden increase of load and which may be immediately started under load upon the opening of a control valve.

A still further object of the invention is to provide an improved external combustion gas engine having associated as parts thereof automatically actuated accessory devices which enable the engine to operate as a self-contained unitary motor having flexible performance characteristics.

A still further object of the invention is to provide an improved engine of the external combustion gas type which is lubricated by oil contained within the compressed gas system and which circulates over the moving surfaces of the gas engine during its operation without coming into contact with ambient air or without being elevated to high temperatures.

It is a further object of this invention to provide an improved external combustion gas engine comprising a thermo-gas compressing unit for supplying gas under pressure to operate a gas engine wherein an inert gas is employed as the working medium in order to prevent corrosion of the parts with which the gaseous medium makes contact and to eliminate deterioration of lubricants during operation of the engine.

A still further object of the invention is to provide an external combustion gas unit which supplies, in addition to output power, both a

cold medium which may be used for refrigeration and cooling of confined spaces, and a hot medium which may be utilized for heating confined spaces.

A still further object of the invention is to provide an improved thermo-gas compressing unit provided with heat transfer means which enable the gaseous medium within the unit to be heated and cooled with a minimum loss of heat and in a minimum amount of time.

A still further object of the invention is to provide an improved gas moving plunger for use in a gas compressing unit which is designed to reduce the flowage of heat through the plunger from the hot head or end of the thermo-gas compressing cylinder to the cold head or end.

A still further object of the invention is to provide an improved heat exchanging unit which will efficiently transfer a large amount of heat from the external heat source to the gas within the thermo-gas compressing unit.

A still further object of the invention is to provide improved heat exchange units which may be inexpensively fabricated, are efficient in operation, and are easily inserted in both the compressed gas and coolant lines of the external combustion gas engine.

A still further object of the invention is to provide an improved external combustion gas engine in which combustion takes place in a chamber the intake and discharge passages of which are constructed to suppress noise, to offer negligible resistance to the flow of gases, and to prevent the possibility of igniting gas or other material outside the combustion chamber.

A still further object of the invention is to provide an improved engine of the external combustion gas type which may be effectively employed as a power source for automotive vehicles in lieu of, and as a substitute for, the conventional internal combustion gas engine, speed changing transmission, clutch and differential gearing.

A still further object of the invention is to provide an external combustion gas engine which may be constructed of relatively few parts that may be easily and quickly assembled and disassembled for inspection and replacement of worn parts.

The invention also resides in certain novel structural characteristics which facilitate the carrying out of the foregoing objects and which contribute both to the versatility of performance and to its ruggedness of construction as well as to its dependability and efficiency of operation.

Other objects and advantages of the invention will become apparent from the following detailed description taken in connection with the accompanying drawings, in which:

Fig. 1 is a diagrammatic drawing of the improved external combustion gas engine showing the accessory devices therefore and the gas engine from which the power output is derived.

While this invention is susceptible of various modifications and constructions, I have shown in the drawings and will herein describe in detail the preferred embodiment. It is to be understood that I do not intend to limit the invention by such disclosure and I aim to cover all modifications and alternative construction falling within the scope and spirit of the invention as defined in the appended claims.

In reference to Fig. 1, the thermo-gas compressing unit is indicated by reference numeral 1. The gas drawn into the thermo-gas compressing unit is obtained from gas containing receiver 56 and after compression within the unit it flows to gas containing receiver 60. The gas employed in this flow cycle may consist of air or may be selected from inert gases such as nitrogen, helium, carbon dioxide or the like. The output of the external combustion gas engine is derived from the shaft of the gas engine 100 which is directly connected through piping and control valves to the gas containing receiver 60 and its exhaust outlet is connected by piping to gas containing receiver 56. Gas engine 100 may be a reciprocating non-expansion, or expansion engine, or it may be of the turbine type. For the purpose of this disclosure, engine 100 will be described as a reversible, multi-cylinder, single expansion, compressed gas motor. An auxiliary compressed gas motor 20 is also connected to the gas containing receiver 60 and the power output of this motor is employed to operate the gas moving plunger 2, a combustion air blower 35 and an auxiliary gas compressor 90, as well as the valve 31 of the auxiliary compressed gas motor 20. Additional control devices are employed in the engine, including a thermostatic fuel control 77, a pressure ratio fuel control device 55, an unloader valve 85, auxiliary gas compressor 90, pressure control mechanism 123, together with the necessary compressed gas control valves.

In more detail the improved engine shown in

Fig. 1 employs a thermo-gas compressing unit having a cylinder 15, provided with a cold body or head 7 at one end thereof and a hot body or head 3 at the opposite end thereof. In heat exchange relation with the hot head of cylinder 15 is a combustion chamber 40 provided with an enclosing wall 16 and a conventional high temperature lining 17. Within the combustion chamber 40 is a fuel burner 18. Air to support combustion is supplied to combustion chamber 40 by blower 35, outlet thereof 36, and inlet 38 of the combustion chamber. The products of combustion or flue gases pass from the combustion chamber 40 through heat exchange passages 341, outlet 42 to the flue or stack 43. As is shown in Fig. 1, both the incoming combustion air and outgoing products of combustion are passed through a heat exchange unit 37, the construction of which will be later described in detail.

The interior of the cylinder 15 of the thermo-gas compressing unit 1 is divided into two chambers indicated by reference numerals 10 and 11 by a movable loosely fitting gas moving plunger 2. This plunger is dimensioned to move in the cylinder in very close proximity to the wall thereof without making actual contact. Chamber 10 is positioned adjacent to the hot cylinder head 3 of cylinder 15 and chamber 11 is positioned adjacent to the cold cylinder head 7. The gas moving plunger or piston 2, which does not serve to compress the gas within cylinder 15 but serves only to move the gas from chamber 10 to chamber 11 and vice versa, is operated by a piston rod 24 which extends through a bore and packing gland 19 of the cold cylinder head 7.

The hot head 3 of cylinder 15 and the associated heat exchange unit are shown in detail in Figs. 9, 10 and 11, and comprise on the combustion chamber side thereof a plurality of radially extended passages 341. The heat resistant lining 17 of the combustion chamber 40 abuts against the lower side of the hot cylinder head 3 to form a barrier which serves to direct the combustion gases through radial passages 341 so that the heat of the gases will be absorbed by the material of the hot head 3. The portion of the hot cylinder head 3 positioned within chamber 10 is likewise formed with radially extending passages 304 which serve as heat exchange means for transferring heat to the gas within chamber 10. As is shown in Figs. 1 and 10, passages 304 extend from an opening positioned in the chamber 10 centrally of the hot cylinder head 3. The hot cylinder head 3 is formed of heat conductive material which will retain its rigidity and force at extremely high operating temperatures.

The radially extending gas passages 304 communicate with a plurality of passages 5 formed of heat absorbing material positioned around the interior wall of cylinder 15. These passages and the material in which they are positioned form the regenerator of the improved engine and serve alternately to absorb and liberate heat during the periodic transfer of gas between chambers 10 and 11. Passages 5 communicate on the cold end of the cylinder with passages 406 preferably formed integral with cold cylinder head 7. The passages 406 extend in a radial direction from the opening 407 positioned in the central portion of the cylinder head 7. Thus, passages 406 in the cold cylinder head, passages 5 adjacent to the wall of cylinder 15, and passages 304 formed integral with hot cylinder head 3, constitute communicating paths between cylinder chambers 10 and 11 through which the gas within the cylinder is

transferred by reciprocating movement of the gas moving plunger 2.

The cold cylinder head 7 is provided with a hollow interior as is indicated by reference numeral 9 through which a coolant is passed. The coolant may comprise any suitable fluid which will serve to transmit heat from the portion of head 7 through which heat passes from the interior of chamber 11. The coolant containing space is connected by pipes 8 to a heat exchange unit 314 which is best shown in Figs. 7 and 8. Flow of coolant in the closed system through pipes 8 between the heat exchange unit 314 and chamber 9 results in the transfer of heat from chamber 11 to the heat exchanger from which it is liberated to the space in which the heat exchange device is located. The details of the heat exchange unit 314 shown in Fig. 1 will be described later.

As the gas moving plunger 2 is moved from a position adjacent to a cold cylinder head 7 to a position adjacent to a hot cylinder head 3, hot gas from chamber 10 is forced through passages 304, the passages of heat regenerator 5, and passages 406, and to chamber 11. A large portion of the heat contained in the gas being thus transferred or moved is absorbed by the regenerator material during its flow through passages 5 and additional heat in the gas is absorbed during flow through passages 406 and dissipated by the coolant flowing in the chamber 9 of the cold cylinder head 7. As the gas cools the pressure falls below the pressure of the gas in receiver 50 and thus check valve 13 opens to permit gas to be withdrawn from receiver 50 through pipe 51, check valve 13, and pipe 12 into chamber 11.

As the gas moving plunger 2 is moved from a position within chamber 10 adjacent to hot cylinder head 3 to a position within chamber 11 adjacent to cold cylinder head 7, the cooled gas flows in an opposite direction; i. e., through passages 406, the passages within the heat regenerator 5 and passages 304 to chamber 10. During this period of flow through passages 5, the heat stored in the regenerator is liberated and the gas temperature is raised. It is further increased during flow through passages 304 since these are in direct heat transfer relation with the combustion chamber 40. As a result of the increase in gas temperature, the pressure rises to that in receiver 60 so that gas is discharged from chamber 11 through pipe 12, check valve 14 and pipe 61 to gas containing receiver 60. Thus, a pressure differential is established in receivers 50 and 60 which is utilized in operating the gas engine 100 as will be hereinafter described.

As has previously been described, the gas moving plunger 2 is reciprocated in cylinder 15 by an auxiliary compressed gas motor 20 which is actuated by the compressed gas from receiver 60. This gas passes to the auxiliary compressed gas motor 20 through check valve 110, pressure control mechanism 123, pipe 111, and valve chest 39 of motor 20. Piston valve 31 controls the direction of flow of compressed gas so that it will act upon opposite faces of piston 21 of motor 20. The reciprocating motion of piston 21 operates piston rod 22 which is connected to rocking beam 23. This beam is fulcrumed at 66 and has its opposite arm connected to piston rod 24 of gas moving plunger 2 by any suitable connecting means. A bell crank 29 also fulcrumed at 66 has one arm connected through a pivotal connection 67 to a linkage 30 which is connected

to the operating rod of piston valve 31. The opposite arm of bell crank 29 is pivotally connected at 68 to rod 28 which in turn is connected to crank arm 25. A flywheel 32 is mounted for rotation on shaft 27 and power is applied thereto by crank arm 25 which is pivotally connected to the rocking beam 23 and crank 26 which is attached to flywheel 32. Thus, motion of the reciprocating piston 21 in auxiliary compressed gas motor 20 is transmitted through piston rod 22 to rocking beam 23 whereby gas moving plunger 2 is reciprocated within cylinder 15, the flywheel 32 is driven by crank arm 25 and piston valve 31 is actuated through bell crank 29, pivotal connection 67 and linkage 30. The rotary motion of the flywheel 32 derived in this manner serves to operate the fan of combustion blower 35 through belt 33 and pulley 34.

The reciprocating movement of piston 21 is also transferred through piston rod 22 to piston 91 which is mounted for reciprocating movement in the cylinder 94 of auxiliary gas compressor 90. Reciprocating movement of piston 91 serves to draw gas through pipe 86, valves 92, to the cylinder 94 from which it is discharged, through valves 83 into gas containing receiver 80 through pipe 81.

The operation of auxiliary gas compressor 90 in the manner described serves to pump gas from pipe 86. When valve 140 is closed the gas in pipe 86 will be evacuated, after which the gas compressor 90 will become inoperative. If valve 140 is open, and the pressure in gas containing receiver 50 is greater than atmospheric, gas will be pumped from receiver 50 by gas compressor 90 to receiver 80. The flow of gas during this pumping operation may be traced from receiver 50 through pipe 113, heat exchange unit 135, the central opening of piston valve 401, valve chest 105, the central opening of second piston valve 101, pipe 112, valve chest 39, the central opening in piston valve 31, pipe 141, valve 140, to pipe 86 and the auxiliary gas compressor 90. Upon the reduction of pressure within receiver 50 to a predetermined value below that of atmospheric pressure, compressor 90 will become inoperative. This reduction in pressure in receiver 50 is reflected in receiver 60 and also in the thermo-gas compressing unit 1, and results in the slowing to idling speed of compressed gas motor 20, compressing unit 1, and combustion blower 35.

If, however, the pressure in receiver 60 is less than the predetermined pressure setting of pressure controlled unloader valve 85, the check valve 84 will open to allow atmospheric air to enter pipe 86 which will be compressed by compressor 90 and discharged to receiver 80. It will be noted that the compressor unloader valve 85 is connected to pipe 81 and the pressure of receiver 80 is communicated to pressure diaphragm 82. When this pressure is increased to a value greater than the preselected value as determined by the weight setting, the check valve actuator 83 is operated to maintain valve 84 in closed position. When, however, the selected pressure value is less than the pressure in receiver 80, the valve actuating rod 83 is moved by diaphragm 82 to permit check valve 84 to open, and thus permit atmospheric air to enter line 86. In this manner, make-up air is admitted to replenish the loss of gas due to possible leakage in the system. If the working gas medium of the engine comprises an inert gas as previously discussed, the inert gas from any suitable container is fed to un-

loader valve 85 and permitted to flow through valve 84 in lieu of the atmospheric air.

As previously set forth, gas engine 100 may be either an expansion or non-expansion type engine or it may be of the turbine type employing a rotor. For the purpose of understanding this invention, engine 100 will be described as a reversible, multi-cylinder, single expansion compressed gas motor such as is conventionally employed to derive power from compressed air or steam. The engine as shown in Fig. 1 is provided with two cylinders 114 and 115 each of which is equipped with a piston 102 which is adapted to reciprocate within its respective cylinder. The pistons are connected by piston rods 103 to connecting rods 104 by cross head pins 116. The reciprocating movement of pistons 102 is employed to drive output shaft 106 which is driven through cranks 117 and 118. These cranks are angularly offset by approximately 90 degrees in order to provide uniform torque during each revolution and to eliminate the disadvantage which would otherwise occur if the pistons came to rest on dead center. Piston valves 101 are provided in valve chest 105 and are reciprocated by valve stems 108 which are connected to eccentric rods 107 by reversing links 119. The eccentric rods 107 are driven by eccentrics 125 which in turn are driven from the crank shaft 106.

Gas engine 100 is connected to receivers 60 and 80 by pipes 132 and 121, and connections 126 and 127. The main throttle valve 120 for the engine is connected to pipes 132 and 121, and located intermediate the engine and connection 126. The gas engine 100 exhausts through pipe 113 which is connected to receiver 50. Heat exchange unit 135 is connected in pipe 113 as shown in Fig. 1. This unit is similar in construction to heat exchange unit 37 and its function will be described in detail later.

Pressure control mechanism 123 is connected to pipe 121 by piping 122 and on the opposite side thereof to connection 126, whereby, as will be seen in Fig. 1, it is placed in parallel relation with main throttle valve 120. Thus the pressure across valve 120 will react on piston 128 of the pressure controlled mechanism 123 and when the pressure different on the opposite sides of valve 120 is reduced the pressure exerted by spring 124 will move piston 128 and piston rod 129 to operate valves 130 and 140. It will be noted that movement of piston rod 129 acts through a toggle connection 131 to rotate the actuating arms of valves 130 and 140. The operation of the pressure controlled mechanism 123 as well as the purpose of valves 130 and 140 will become apparent during the description of the engine operation.

The fuel supplied through pipes 75 and 76 from a source (not shown) to fuel burner 18 in combustion chamber 40 is controlled by a thermostatic fuel control device 77 and a pressure ratio fuel control device 55. The thermostatic fuel control device 77 comprises an extensible bellows 71, the interior of which is connected to a bulb 70 positioned in the outlet 42 of the combustion chamber. The interior of bulb 70 and bellows 71 is filled with an expansible fluid which causes the bellows to expand when the bulb 70 is affected by increased temperatures. A valve 72 is actuated by bellows 71 to close the fuel supply pipe 76 upon the occurrence of a predetermined temperature within the outlet of the combustion chamber. Upon the occurrence of temperatures

less than a predetermined value the bellows contract to open valve 72 and permit fuel to flow from the source to burner 18.

The differential pressure ratio fuel control valve 65 which also serves to control the flow of fuel to burner 18 is directly connected with opposing diaphragms 52 and 62. One side of diaphragm 52 is connected directly to, and affected by the pressure in gas containing receiver 50 and the opposing side of diaphragm 62 is connected to and affected by the pressure existing in gas containing receiver 60. These diaphragms are connected by the valve rod 56 which actuates the pressure ratio fuel control valve 65. As is shown in Fig. 1, diaphragm 52 has a greater area than that of diaphragm 62. By this opposed arrangement of diaphragms, pressure ratio fuel control valve 65 is caused to close when the pressure in receiver 60 multiplied by the area of diaphragm 62 is greater than the pressure of receiver 50 multiplied by the area of diaphragm 52. Conversely, control valve 65 will be opened to permit fuel to flow to burner 18 through pipes 75 and 76 when the pressure in receiver 50 multiplied by the area of diaphragm 52 is greater than the pressure of receiver 60 multiplied by the area of diaphragm 62. By this arrangement a ratio of pressure existing in receivers 50 and 60 may be selected above which control valve 65 will be closed and below which this valve will be opened to permit the flow of fuel to burner 18.

The details of construction of the heat exchange unit 37 are shown in Figs. 2 to 6 inclusive, wherein reference numeral 236 (Fig. 2) indicates the inlet for the combustion air from the blower 35, and reference numeral 238 represents the outlet to the combustion chamber inlet 38. Numeral 242 indicates the inlet to the heat exchange unit for the products of combustion received from outlet 42 of the combustion chamber, and numeral 243 represents the outlet from the heat exchange unit 37 to the flue or stack 43. It will be apparent that the passages will be closed by suitable plates (not shown) positioned on the opposite sides of the heat exchange unit from the inlets and outlets above described in order that the gases will be directed and flow through the passages provided in the unit. Air to the combustion chamber and the products of combustion from the combustion chamber flow in opposite directions through the heat exchanger in order to increase the exchange of heat between the gases in the unit. The heat exchange unit 37 is built up of a plurality of formed sheets 237 which are secured between face plates 202 by rivets or bolts 209. The sheets 237 which form the heat exchange surface of the unit are preformed as indicated in Figs. 3 to 5 inclusive and each adjacent sheet is reversed in position in order to form spaces therebetween for the combustion air entering the combustion chamber and for the products of combustion leaving the combustion chamber. The plurality of sheets 237 are secured in superimposed relation between plates 202 by rivets or bolts 209. The spaces between the sheet groupings through which the gases enter and leave the heat exchanger are formed by the use of spacer rings 206 best shown in Fig. 6. The spacer rings are provided with apertures 216 and one of the rings is positioned between each group of two sheets except for the plates at the top and bottom of the heat exchange unit.

As will be observed in Figs. 2 to 6, inclusive, the preformed heat conducting sheets 237 are ar-

ranged in pairs and a plurality of the pairs are secured in superimposed relation between the face plates. Each of the conducting sheets is formed from a flat sheet and is provided with depressed and raised sections located adjacent to diagonal corners, and each section contains an opening therein. The sheets 237 are assembled with the depressed portions of pairs thereof in alignment and in engagement with each other to provide spacing means between sheets adjacent to each pair of sheets. Apertured spacing rings 206 are positioned in the recesses or chamber formed by the aligned raised portions, and spacing washers are located intermediate the raised and depressed sections and positioned between the flat surfaces of adjacent sheets. Additional spacing elements 203 and 204 are positioned between the sheets 237 to seal the perimeter of the heat exchange unit when the individual sheets are secured in assembled position.

By this construction the gases entering through the openings 236 and 242, flow in opposite directions through adjacent passages formed by the sheet groupings and leave the heat exchange unit by openings 238 and 243. Thus the air for supporting combustion within the combustion chamber is preheated by passing over the surfaces of the heat exchanger which are heated by the products of combustion leaving the combustion chamber at 42. In view of the fact that the air enters and the products of combustion leave through the narrow passages between the closely spaced sheets 237 of the heat exchange unit, noise due to combustion will be suppressed and the gases will be cooled to prevent the possibility of igniting any gas or other material outside the combustion chamber.

The heat exchange unit indicated by reference numeral 135 in Fig. 1 is similar in construction to heat exchange unit 37, just described.

The details of heat exchange unit 314 are shown in Figs. 6 to 8 inclusive, wherein numerals 308 indicate the entrance and exit for coolant from cool cylinder head 7, Fig. 1. This heat exchange unit is built up of a plurality of formed sheets 337, spacing washers 307, and spacing rings 206, which are secured between face plates 302 by bolts or rivets 309. The sheets 337 which are preformed with raised and depressed sections having holes therethrough, as shown in Fig. 8, are assembled in superimposed relationship and secured together between face plates 302 in a manner similar to the heat exchanger 37. Spacing rings 206 having apertures 216 are placed adjacent the ends of this heat exchanger between pairs of sheets 337. The sides and terminal extremities of pairs of adjacent sheets are welded together as is indicated by reference numeral 338 in order to obtain a fluid-tight structure for the coolant. Air for cooling may flow either by convection or forced draft between these pairs of sheets. The air passing through heat exchange unit 314 will be increased in temperature by the heat removed from the cold cylinder head 7 of the thermo-gas compressing unit 1. This heat will be available for increasing the temperature of a confined space, such for example, as the interior of a vehicle during the operation of the external combustion gas engine.

Since in any expansible gas engine power is produced at the expense of sensible heat energy, the temperature of the gas is reduced during its passage through these engines. This pressure-temperature relation for gases remote from

their liquefaction temperatures is given approximately by the formula

$$\left(\frac{P_1}{P_2}\right)^4 = \frac{T_1}{T_2}$$

where P_1 and P_2 are absolute pressures, and T_1 and T_2 are absolute temperatures.

For the pressure ratios used in these engines, this gives a very substantial temperature drop so that the gas leaving engine 100 and flowing through heat exchanger 135 will be much lower than the ambient temperature. Any fluid medium which is circulated from connection 133 to 134 through heat exchanger 135 may be employed to refrigerate confined spaces such, for example, as the interior of a vehicle body.

Details of the preferred embodiments of the loosely fitting gas moving plunger 2 are shown in Figs. 12 and 14. As shown in Fig. 12, the gas moving plunger is represented by reference numeral 402 and comprises a hollow cylinder closed at both ends to form chamber 400. In order to decrease the heat transfer through the gas moving plunger 402, the interior surfaces thereof are finished to present a highly reflective surface and the interior 400 is evacuated to a high degree. Gas moving plunger 402 is connected to piston rod 424 which passes through cold cylinder head 7 in which gas passages 406 and coolant passages or chambers 409 are provided. In order that the interior of the thermo-gas compressing unit may be tightly sealed, packing 425 and gland 426 are employed through which piston rod 424 passes. Gas passages 406 radiate from a central opening 407 as is shown in Fig. 13 and the entire cylinder head in which the radial passages are integrally formed is bolted to thermo-gas compressing cylinder 1 by bolts which pass through holes 401 in the circumference of the cylinder head.

Fig. 14 discloses a preferred embodiment of the gas moving plunger 2 and cold cylinder head 7 wherein the gas transferred by plunger 402 is subjected to additional cooling surface. In this embodiment the gas moving plunger 402 is formed in a generally cup shape with the interior thereof provided with a reflective surface and the interior thereof evacuated to the extent previously explained. The coolant passages 409 are elongated along the axis of piston rod 424 and gas passages 406 are positioned circumferentially about the coolant passage 409. When the gas moving plunger 402 is moved toward the cold cylinder head 7, the coolant chamber 409 and the gas passages 406 are positioned in the recess portion of the gas moving plunger 402. In this embodiment the coolant surface adjacent the gas passages has been greatly increased in order that heat in the gas entering portion 11 of the thermo-gas compressing cylinder will be more effectively removed. The relation of the coolant chamber 409 and gas passages 406 is shown in Fig. 15 wherein the apertures 401 for securing the cold cylinder head in place on cylinder 15 are shown. In a similar manner, the gas moving plunger shown in Fig. 14 is secured to a piston rod 424 which passes through a packing 425 which is maintained under pressure by packing gland 426. The coolant leaves and enters a chamber 409 through inlet and outlet 408.

The operation of this external combustion gas engine is as follows:

It being assumed that the valve 12 of the thermostatic fuel control device 17 and valve 65 of pressure ratio fuel control device 55 are open and fuel is flowing through pipe 75 and 76 to

burner 18, the engine may be started by manually lighting burner 18 and manually turning shaft 27. In lieu of manual starting, conventional electrical means (not shown) may be used, such as a starting motor for rotating fly wheel 32 and either a hot wire, or spark gap may be employed to ignite burner 18.

Operation of air blower 35 forces air to support combustion through heat exchange unit 37 to burner 18, and thence to combustion chamber 40. The products of combustion flow through passages 341, thus heating the hot cylinder head 3. The gas contained in portion 10 of cylinder 15 of the thermo-gas compressing unit 1 will be heated by the heat conducted through cylinder head 3. The reciprocation of the gas moving plunger 2 in cylinder 15 by its connected mechanical linkage will cause, upon a downward stroke of the plunger, the heated gas to flow through radial passages 304, the elongated passages 5 of the heat regenerator, and passages 406, located in the cold cylinder head 7. As the gas is moved through the regenerator 5, a certain amount of the heat is absorbed and additional amounts of heat are absorbed by the coolant in passage 409 of the cold cylinder head as the gas passes through radial passages 403. Thus the gas which reaches chamber 11 of cylinder 15 is reduced in temperature and the resulting drop in pressure causes gas to be drawn through pipe 12, check valve 13, pipe 51 from receiver 50. Upward movement of the gas moving plunger 2 causes the cooled gas in chamber 11 to flow through radial passages 406, the elongated passages of heat regenerator 5 and the radial passages 304 to chamber 10 of cylinder 15. During this flow of gas the heat regenerator liberates heat to the flowing gas and upon reaching portion 10 after flowing through radial passage 304 the gas is elevated in temperature, and the pressure is correspondingly increased. As a result, the increase in pressure causes a portion of the gas confined in cylinder 15 to flow from the cylinder through pipe 12, check valve 14, pipe 61, into receiver 60. Repeated strokes of the gas moving plunger 2 thus cause an appreciable amount of gas to be pumped from receiver 50 into receiver 60 and thus a definite pressure ratio is built up between the gases in the two receivers. As the pressure builds up in receiver 60, gas flows through check valve 110 of connection 126, pressure control mechanism 123, pipe 111, to auxiliary compressed gas motor 20. The gas under pressure acts through piston valve 31, upon piston 21, to cause it to reciprocate within its cylinder. Motor 20 is mechanically linked, as heretofore described, with flywheel 32, gas moving plunger 2 and auxiliary gas compressor 90. The movement of piston rod 22 thus causes plunger 2 to reciprocate in cylinder 15, and also causes piston 91 to operate in cylinder 94 of the compressor 90. Operation of the compressor 90 serves to pump gas from receiver 50 into receiver 80. The path of the gas during this pumping operation is from receiver 50, through pipe 113, heat interchanger 135, valve chest 105, pipe 112, the valve chest 99 of compressed gas motor 20, pipe 141, valve 149, pipe 86, inlet valve 92, cylinder 94, discharge valve 93, pipe 81, connection 127, to receiver 80. Continued operation of the auxiliary gas compressor 90 serves to increase the pressure in receiver 80 and to reduce the pressure in receiver 50 which in turn causes a reduction of pressure in the thermo-gas compressing unit 1 and the re-

ceiver 60. When the pressure in receiver 50 falls below atmospheric pressure, check valve 84 of unloader valve 85 opens to permit atmospheric air or other gas as previously described to be drawn into pipe 86 and to be pumped into receiver 80 through pipe 81. The continued operation of auxiliary gas compressor 90 builds up the pressure in receiver 80 until diaphragm 82 is extended against a lever which is set for a predetermined pressure in receiver 60. When this pressure is attained, diaphragm 82 will be extended and check valve actuator 83 will move to close check valve 84.

As auxiliary gas compressor 90 continues to operate pipe 86 and the connecting lines will be evacuated down to the point where compressor 90 becomes inoperative. The reduction of pressure in receiver 50 affects diaphragm 52 and permits the opposing diaphragm 62 to move the valve rod 56 to close valve 65. Closure of valve 65 reduces the flow of fuel to burner 18 to an amount which is just sufficient for idling operation. The thermo-gas compressing unit and the auxiliary motor and pump will continue to operate in this manner under idling conditions as long as the throttle valve 120 remains closed.

Gas engine 100 is started by opening valve 120 which permits compressed gas from receiver 60 to flow through check valve 110, connection 126, pipe 132, valve 120, and pipe 121, to the valve chest 105. The exhaust from the engine flows through pipe 113 and the heat interchanger 135 to receiver 50. Flow of compressed gas to valve chest 105 serves to initiate operation of the engine which results in rotation of crank shaft 106. When valve 120 is partially opened and a light torque is applied to crank shaft 106 material pressure difference exists in pipe 132 and 121 across the valve 120, piston 128 which is affected by the pressure in receiver 60 remains in the position shown in Fig. 1, i. e., spring 124 is compressed and piston rod 129 is positioned to maintain valve 140 in an open position and valve 130 in a closed position. When increased torque is applied to the crank shaft 106 and the throttle valve 120 is in a partially open position, the pressure in pipe 121 builds up in respect to the pressure in pipe 132. Under this operating condition compression spring 124, plus the increased pressure existing in pipe 122, serves to move piston 128 of the pressure control mechanism 123 to close valve 140 and open valve 130. This permits gas from receiver 60 to flow through connections 127 and 126, pipe 132, throttle valve 120, and pipe 121, to gas engine 100. The increased pressure from receiver 60 serves to operate engine 100 at the increased output torque. As the engine comes up to speed under the increased load the pressure differential across valve 120 is partially restored and piston 128 is moved to compress spring 124. This action serves to close valve 130 which will remain closed until greater torque is required.

If materially less torque is required, the pressure differential across valve 120 is increased and piston 128 will move to the extremity of the cylinder to further compress spring 124. The resultant movement of piston rod 129 serves to move the toggle connection 131 to open valve 140. The opening of valve 140 completes a flow path from receiver 50 to receiver 80 via the auxiliary gas compressor 90, as previously explained. Operation of the compressor serves to decrease the pressure of the gas in receiver 50 which again

reduces the pressure differential across throttle valve 120 and also on opposite sides of piston 128, thus allowing spring 124 to move piston 128 to close valve 140. During this latter operation, valve 130 has remained closed, due to the lost motion in toggle connection 131, which is operated by the piston rod 129. This condition of operation continues until a change of torque occurs on the output shaft of gas engine 100, or until the setting of the throttle valve 120 is changed.

Increased opening of the throttle valve 120 will decrease the pressure differential across the valve, and piston 128 will operate in the manner described as a function of the pressure differential to open valve 130. This results in raising the pressure of the gas supplied to gas engine 100 which causes the motor to accelerate. As the motor accelerates the flow of gas in pipe 121 increases, which serves to re-establish the pressure differential across throttle valve 120. Thus it will be apparent that the speed of engine 100 is maintained substantially proportional to the throttle valve opening.

The opening of throttle valve 120 as above described also results in a lowering of the pressure differential existing between receivers 60 and 50. Since the pressure existing within these two receivers actuates the differential pressure ratio fuel control valve 65, it will be apparent that an increase of pressure in receiver 50 and its resultant effect on diaphragm 52 will serve to overcome the opposed force on diaphragm 62 resulting in the opening of valve 65 to permit an increased fuel flow to burner 18. Valve 65 remains open as long as the ratio of pressure in receivers 50 and 60 remains below a predetermined value. As increased fuel is fed to burner 18, the temperature developed in combustion chamber 50 is raised; this increases the temperature difference between the hot and cold ends of cylinder 15 which in turn increases the volumetric efficiency of the compressing unit to meet the demands of gas engine 100.

When the hot cylinder head 3 attains its working temperature, the thermostatic fuel control device 77 influenced by the expansion of fluid in bulb 78 comes into operation to maintain the desired temperature of hot cylinder head 3 by controlling the operation of valve 72 in the fuel supply line. Thus the thermostatic fuel control device 77 serves as a control to maintain the temperature of hot cylinder head 3 substantially constant during varying load conditions upon the external combustion gas engine. Increased loading of the engine will result in increased heat transfer by the gas in cylinder 15 and decreased loading of the engine will result in a lowering of heat transfer by the gas in cylinder 15. Since an increase in the opening of throttle valve 120 serves to speed up engine 100 and its accessories, the output of blower 35 will be increased to supply the necessary combustion air to burner 18.

When the throttle valve 120 is closed after gas engine 100 has been in operation, the components of the external combustion gas engine are automatically placed in idling or stand-by condition. Since the closure of valve 120 decreases the flow of gas from receiver 60 and the operation of the thermo-gas compressing unit continues to pump gas from receiver 50 into receiver 60, the pressure ratio existing between these receivers is increased and the pressure ratio fuel control valve 65 is actuated as a result of this pressure ratio to decrease the supply of fuel to burner 18. Upon

decrease of fuel the temperature of hot cylinder head 3 decreases which in turn results in a decrease in the ratio between the temperatures of the cold and hot cylinder heads. As the temperature differential is decreased between the hot and cold cylinder heads of the thermo-gas compressing unit 1, the pressure ratio will also be reduced to the predetermined value which is required to be maintained in the receivers 50 and 60 for idling conditions.

Confined spaces may be readily heated by the air used to absorb heat from the coolant which flows through heat exchange unit 314. This absorbed heat is removed from the cold end of the thermo-gas compressing unit and comprises that heat which must be discarded in any heat engine. The coolant flowing in the jacket or chamber of the cold cylinder head and through the heat exchange unit 314 may comprise water or any suitable low freezing point liquid, which is normally employed in the cooling system of an internal combustion engine. Additionally, the coolant may be a gas, such as air, which will serve as a heat transfer medium. In view of the fact that the exhaust gas flowing from gas engine 100 through pipe 113 to receiver 50 has a low temperature, the heat exchange unit 135 positioned in pipe 113 may be employed for cooling purposes. This refrigerating effect may be utilized to cool any fluid entering the heat exchange unit 135 at 133 and leaving through the outlet pipe 134. Thus, a confined space located a distance from the heat exchange unit 135 may be cooled by the passage of the cooled fluid through a heat exchanger in the form of a conventional radiator, or air may be forced through inlet 133 and outlet pipe 134 to obtain directly the refrigerating effect.

Pistons 102 and valves 101 of gas engine 100 are preferably lubricated by oil or other flowable lubricant positioned within the closed gas circuit between receivers 50 and 60. Operation of the thermo-gas compressing unit 1 may serve to draw oil through pipe 51 from receiver 50 which will pass through check valves 13 and 14 and be returned to receiver 60 through pipe 61. During operating of gas engine 100 this lubricant will pass through check valve 110, connection 126, pipe 132, valve 120 and pipe 121 to engine 100. Further, a portion of the lubricant will flow from receiver 60 through pipe 111 to the auxiliary compressed gas motor 28, pipes 141 and 36, to the auxiliary gas compressor 98 and then to receiver 80. In this manner the gas engine 100 and the auxiliary devices will be automatically lubricated during their operation. The lubricant will be circulated without being unduly heated or contaminated by contact with ambient air.

The employment of an inert gas in the closed gas flow system of the engine as has previously been discussed eliminates the possibility of corrosion of the working parts and in addition prevents the deterioration of lubricants due to oxidation.

The aforescribed external combustion gas engine will operate at an efficiency which closely approaches the theoretical value of the efficiency of reversible heat engines which is expressed by the following equation:

$$\text{Eff} = \frac{T_1 - T_2}{T_1}$$

wherein T_1 is the temperature of the gas in chamber 10 of cylinder 15 and T_2 is the temperature of the gas in chamber 11 of cylinder 15. The

radiant heat transferred through gas moving plunger 2 is reduced to a negligible quantity due to the construction of the plunger as previously described. Passage of the flue gases from combustion chamber 40 and air from blower 35 through the heat exchanger 37 serves to remove substantially all of the available heat from these flue gases, and to heat the combustion air so that low quality fuels may be efficiently used. Losses due to either conduction or radiation from the combustion chamber, cylinder 15, and the hot end of heat exchanger 37 are minimized due to the use of adequate heat insulating material about these parts in accordance with insulating practices well known in the art. The temperature of the hot cylinder head is raised to a high value due to the use of heat conductive material which is corrosion resistant at high temperatures. In view of these measures taken to conserve heat energy and to maintain as great a temperature difference as is possible between the opposite ends of cylinder 15, this external combustion gas engine will operate at an efficiency which closely approaches the theoretical limit as expressed in the above equation.

I claim:

1. In a heat exchange device having a plurality of substantially parallel flow paths alternate paths of which are diagonally directed with respect to the adjacent paths, the combination comprising, a plurality of pairs of heat conducting sheets positioned in superimposed relationship, each of said heat conducting sheets being identically shaped and formed with a substantially rectangular contour and provided with an aperture adjacent to each corner thereof, raised portions formed at diagonally opposite corners of said sheets surrounding said apertures, depressed portions formed at the remaining diagonally opposite corners of said sheets surrounding said apertures, said pairs of heat conducting sheets positioned with the diagonally positioned raised portions in fluid tight contact and with the apertures therein located in alignment, a spacing ring having radial openings therein positioned between the pairs of sheets within the recesses formed by the diagonally positioned depressed portions and around the edge of said apertures, means forming a fluid tight connection between the outside edges of said sheets, and means to secure said sheets and spacing rings in the aforedefined position.

2. In a heat exchange device having a plurality of substantially parallel flow paths alternate paths of which are diagonally directed with respect to the adjacent paths, the combination comprising, a plurality of pairs of heat conducting sheets positioned in superimposed relationship, each of said heat conducting sheets being identically shaped and formed with a substantially rectangular contour and provided with an aperture adjacent to each corner thereof, raised portions formed at diagonally opposite corners of said sheets surrounding said apertures, depressed portions formed at the remaining diagonally opposite corners of said sheets surrounding said apertures, said pairs of heat conducting sheets positioned with the diagonally positioned raised portions in fluid tight contact and with the apertures therein located in alignment, a spacing ring having radial openings therein positioned between the pairs of sheets within the recesses formed by the diagonally positioned depressed portions and around the edge of said apertures, means forming a fluid tight connection between

the outside edges of said sheets, face plates positioned on sides of said superimposed heat conducting sheets having openings therethrough in alignment with said apertures in said heat conducting sheets, and means extending through said plates and sheets for securing the heat exchange elements in position.

3. A heat exchange device comprising a plurality of pairs of identically shaped, substantially rectangular sheets positioned in superimposed relationship between face plates, each of the sheets comprising said pairs being formed of substantially flat heat conducting material and provided with depressed sections located adjacent to diagonally opposite corners and with raised sections located adjacent to the other opposite corners of the rectangular sheet, each of said raised and depressed sections provided with a centrally positioned opening through said material, said sheets of each pair positioned with the depressed sections thereof in engagement with each other and the openings therein in alignment and with the raised sections thereof in engagement with and the openings therein in alignment with the apertured raised sections of the adjacent pair, spacing rings having openings in the side walls thereof positioned within said raised portions and extending between the sheets of each pair and between the aligned depressed sections of the sheets of adjacently positioned pairs, closure means for sealing the peripheral edges between said superimposed flat sheets and openings positioned within said face plates in alignment with the openings in said sheets whereby a plurality of passages are provided between the openings positioned adjacent to diagonally opposite corners of said sheets which are in heat exchange relation with a second group of passages extending between said other diagonal corners of said plates.

4. A heat exchange device comprising a plurality of pairs of identically shaped, substantially rectangular sheets positioned in superimposed relationship between face plates, each of the sheets comprising said pairs being formed of substantially flat heat conducting material and provided with depressed sections located adjacent to diagonally opposite corners and with raised sections located adjacent to the other opposite corners of the rectangular sheet, each of said raised and depressed sections provided with a centrally positioned opening through said material, said sheets of each pair positioned with the depressed sections thereof in engagement with each other and the openings therein in alignment and with the raised sections thereof in engagement with and the openings therein in alignment with the apertured raised sections of the adjacent pair, spacing rings having openings in the side walls thereof positioned within said raised portions and extending between the sheets of each pair and between the aligned depressed sections of the sheets of adjacently positioned pairs, closure means for sealing the peripheral edges between said superimposed flat sheets, a plurality of tightening means extending between said face plates and through said superimposed flat sheets provided with a spacing washer positioned between each of said sheets for securing said pairs and plates, and openings positioned within said face plates in alignment with the openings in said sheets whereby a plurality of passages are provided between the openings positioned adjacent to diagonally opposite corners of said sheets which are in heat exchange relation with a second group of pas-

sages extending between said other diagonal corners of said plates.

5. A heat exchange device having two series of passages for the flow of separate fluids in an opposed diagonal direction through said passages comprising a plurality of identically shaped sheets, each of said identically shaped sheets having a generally rectangular contour, being formed of heat conducting material having raised sections located a spaced distance from the edges of diagonally opposite corners, having depressed sections located a spaced distance from the edges in the other opposite corners of the sheet and apertures extending through said sheets within said raised and depressed sections, adjacently positioned identically shaped sheets arranged in spaced superimposed relation with corresponding depressed sections in engagement with each other and the apertures therethrough in alignment to provide passages located in diagonal corners of said sheet communicating between said adjacently positioned sheets and with opposite diagonally positioned raised sections and apertures therein in alignment with each other, a spacing ring provided with openings in the side wall thereof positioned between said aligned raised section and around the aligned apertures of each of said adjacently positioned sheets, and closure means located adjacent the edges of said sheets to seal the spaces therebetween.

6. A heat exchange device comprising a plurality of generally rectangular sheets formed of heat conducting material positioned in spaced superimposed relation to define a plurality of passageways between adjacently positioned sheets, means positioned adjacent the edges of said sheets to seal the spaces between each of said sheets, each of said heat conducting sheets having raised sections located a spaced distance from the edges in diagonally opposite corners and depressed sections located a spaced distance from the edges in the other opposite corners of the sheet, said raised and depressed sections provided with apertures extending through said sheets, said adjacently positioned sheets arranged with the corresponding depressed sections in engagement with each other and the apertures therethrough in alignment to provide openings located in diagonal corners of said sheets which communicate between alternate passageways and with the opposite diagonally positioned raised sections and apertures therein in alignment with each other, and a spacing ring provided with openings in the side wall thereof positioned between said aligned raised sections and around said apertures of each of said adjacently positioned sheets.
